Patented July 4, 1967

208,035

OUTDOOR YARD LIGHT HEAD

Harold P. Smith, ½ Plains Aluminum Industries,
Box 38, Panhandle, Tex. 79068

Filed Nov. 16, 1966, Ser. No. 4,693

Term of patent 14 years

(Cl. D48—31)

Fig. 1

Fig. 2

The dotted lines in FIGURES 1 and 3 illustrate a manner of supporting the outdoor yard light head and are for illustrative purposes only.

I claim:

The ornamental design for an outdoor yard light head, as shown and described.
